VEGETABLE JUICER

Henry A. Dewenter, 1477 Old Mill Road,
San Marino, Calif.

Filed Aug. 25, 1961, Ser. No. 66,495

Term of patent 14 years

(Cl. D89—1)

FIG. 1.

FIG. 2.

FIG. 3.

FIG. 1 is a top plan view of the juicer of the present invention;

FIG. 2 is a front elevational view of the juicer shown in FIG. 1; and

FIG. 3 is a rear elevational view of the juicer portion removed from the base portion.

I claim:

The ornamental design for a vegetable juicer, as shown.
